INVENTOR

INVENTOR
F. A. Holmes,

BY
G. S. Kennedy,
ATTORNEY

UNITED STATES PATENT OFFICE

FRANK A. HOLMES, OF WATERLOO, IOWA, ASSIGNOR OF ONE-HALF TO ALBERT J. LYITLE
AND ONE-HALF TO B. B. HUNTER, BOTH OF WATERLOO, IOWA

GRAVE MARKER

Application filed September 2, 1930. Serial No. 479,370.

My invention relates to improvements in grave markers, and other inscription receiving structures, and the object of my improvement is to supply such a member or structure with supporting means assemblable therewith detachably, to secure said member or structure upon the ground surface or other supporting means for visible display thereabove.

Another object of my improvements is to construct and shape said supporting means as end standards or supports having either fixed or detachable vase-like means in hollows thereof to receive flowers, plants or other ornamental or significant things therein, such as may more or less relate to the inscribed matter upon the supported member.

Another object is to furnish suitable closures for the upwardly opening hollows of said standards, and means for fastening said closures thereto.

Another object is to use in combination with said standards soil penetrating anchoring means having cross connecting means to secure the standards interlocked to the inscription receiving intermediate structure, and to thus cooperate with mortise joints therebetween shaped for interlocking connections.

These objects I have accomplished by the means which are hereinafter described and claimed, and which are illustrated in the accompanying drawings, in which Fig. 1 is a front elevation of my improved grave marker, showing its soil penetrating means and their connection therebelow, with parts of the latter in section and other parts in front elevation. Fig. 2 is a vertical longitudinal section of one of the end standards, and part of its ground penetrating support, with other parts broken away or in front elevation. Fig. 3 is a horizontal section of one of said end standards taken on the broken line 3—3 of said Fig. 2.

The numeral 1 denotes an inscription receiving plate, preferably of bronze or other substance of a durable nature, and which may have a marginal thickening as at 2. Each end of this plate has tenons 4 and 5, of which the tenons 4 are widened outwardly by slop-

ing the lower edges for interlocking purposes with the walls of like shaped openings 6 in the upper parts of standards 3, as shown in Fig. 2.

The lower tenons 5 with the mortise openings 7 therefor in the standards 3 are of the usual rectangular shape. The standards 3 may be of any desired outer configuration, preferably ornamental. The standards are also preferably hollowed out with open ends and having seats therein to receive and fit open top vases or containers 8 to receive flowers, plants or other things. Closures 9 are supplied having detents or projections to fit into engaging sockets in the upper edges or rims of the standards, as at 12, and these caps may also be ornamental, hollowed or cupped downwardly and shaped as finials for the standards, being connected thereto by means of short chains 10 and eyes as at 11.

The standards are interlocked with the ends of the plate 1 at their end mortise joints, by inclining tiltingly the standards to allow the upper widened end tenons 4 to enter the mortises 6 in the standards, and then the standards are swung into contact with the plate ends to cause the lower tenons to enter and fit the lower mortises 7. The base of each standard has an interiorly threaded socket 13 to receive an exteriorly threaded upper end 14 of a depending pipe member 15 which is to be planted in the soil as shown in Fig. 1, leaving the plate 1 spaced above the ground level.

The lower part of each pipe 15 may be transversely apertured to seat a short cross projection 19 to serve as anchoring means in the earth. Before thus implanting the pipes 15, cavities may be made in the earth by means of a post-hole digger or other means to receive the pipes, and if desired the cavities may be of larger diameter than the pipes to receive plastic cement or concrete as at 18 embedding the pipe therein, together with the ends of a horizontal connecting and tensioning rod 16 secured by an end nut 17, the shaft of the rod being beneath the ground surface. This rod 17 thus serves as an anchoring member, and also secures the mortise joints in their interlocked positions.

The elements of my device may be of any desired shape or material, and may be inscribed suitably for the purpose, whether for use as a grave marker, or for notices of any kind displayed thereon.

The inscribed member may be integral with a vase-shaped part, or may be constructed of separate parts of those kinds rigidly and permanently united, as well as of detachably connected members of those or differently shaped descriptions.

Having described my invention, what I claim as new, and desire to secure by Letters Patent, is:

- 15 1. In combination, an inscription receiving member, hollow and cupped standards for supporting the ends of said member and releasably secured thereto, hollow liner vases fitting removably in the cupped ends of the standards, top closures for the standards, and depending projections on the standards to enter and serve as anchoring means therefor in the soil below.
- 20 2. In combination, an inscription receiving member, standards secured to the ends thereof having hollow seats, removable containers fitted in said seats, closures for said seats, and flexible connections between said closures and said standards.
- 25 3. In combination, an inscription receiving member, standards hollowed and having releasably interlocking mortise joint connections with the ends of said member, a cupped container mounted in each standard hollow, closures for said hollows having flexible fastening means connected to the standards, anchoring projections depending from the standards, and other anchoring means connected to said projections.
- 30 40 4. In testimony whereof I affix my signature.
FRANK A. HOLMES.
